UNITED STATES PATENT OFFICE.

RAYMOND E. JACOBY, OF PHILADELPHIA, PENNSYLVANIA.

WRENCH.

1,347,780.

Specification of Letters Patent. Patented July 27, 1920.

Application filed July 16, 1919. Serial No. 311,320.

To all whom it may concern:

Be it known that I, RAYMOND E. JACOBY, a citizen of the United States, residing at Philadelphia, in the county of Philadelphia and State of Pennsylvania, have invented 5 certain new and useful Improvements in Wrenches, of which the following is a specification.

The construction and disposition of the 10 engine, its fly wheel, the frame, casing and opening covered by the bottom pan of a Ford car necessitates removing the entire engine from the frame and dismantling it when the fly wheel is loose and the crank shaft 15 bearings have to be taken up. These operations, as at present practised, require the time of two men from a day and a half to two days.

The invention has for one of its objects 20 the provision of a novel wrench constructed so that it may be operated through the opening in the bottom of the casing of the engine of a Ford car for the purpose of removing and replacing the bolts which secure the fly 25 wheel, thus obviating the necessity of removing the engine from its frame and dismantling it when this operation becomes necessary.

A further object is to provide a novel 30 wrench which may be operated through the opening in the bottom of the casing of the engine of a Ford car for the purpose of removing the nuts from the bolts on the third or innermost crank shaft bearing, thus obviating the necessity for taking out the 35 engine and dismantling it when the crank shaft bearings have to be taken up.

My invention has for another object the provision of a novel wrench constructed so 40 as to be adapted to be operated through the opening in the bottom of the casing of a Ford car for the purpose of removing the bolts from the middle crank shaft bearing of the engine of a Ford car without necessitating removal of the engine and dismantling 45 it.

An additional object of my invention is 50 to provide a novel wrench having sockets at its respective ends, enabling it to be used for two different operations, to-wit: first, removing the bolts from the fly wheel of the engine of a Ford car by an operation conducted through an opening in the bottom 55 of the casing thereof; second, removing the bolts from the center crank shaft bearing of the said engine by an operation conducted

through the opening in the bottom of the casing, and for replacing said bolts.

Another object of my invention is the provision of a novel wrench having sockets at 60 its respective ends arranged and adapted so that they may be alternately used in removing the nuts from the inner most crank shaft bearing of the engine of a Ford car by an operation conducted through the opening in 65 the bottom pan thereof.

The limited lateral space available inside the pan of the engine of a Ford car and the relationship of the bottom of the pan to the crank shaft and its bearings has heretofore, 70 so far as I am aware, rendered it impossible to use a wrench or tool for carrying out the operations I have specified and this has necessitated the removal of the engine from its frame and dismantling it when bolts had 75 to be removed from the fly wheel and replaced therein and wear taken up in the crank shaft bearings. So far as I am aware, I am the first to provide a wrench whose construction adapts it for conducting the opera- 80 tions specified.

In the accompanying drawing,

Figure 1 is a side elevation of the rear part of a Ford engine, the casing being broken away showing the wrench of Figs. 2, 85 3, 4 and 8 in position to perform the operation of unscrewing the bolts which attach the fly wheel to the crank shaft;

Fig. 2 a detail side view of the wrench used in the operations represented in Figs. 90 1 and 8;

Fig. 3 a view of the left hand end of the wrench of Fig. 2;

Fig. 4 a similar view of the right hand end of said wrench;

Fig. 5 a view like Fig. 1 showing the manner in which the wrench of Figs. 6 and 7 is operated to remove the nuts from the innermost or third crank shaft bearing;

Figs. 6 and 7 side and plan views, respectively, of the wrench employed to carry out the operation illustrated in Fig. 5;

Fig. 8 a side view, partly broken away, showing a part of the engine and its shell, illustrating how the wrench of Figs. 1 to 4 105 is used when performing the operations of removing or replacing the bolts from the first and intermediate crank shaft bearings, and

Fig. 9 a detail view of a two-part bolt 110 which may be used on the front crank shaft bearing after the usual bolt has been cut off

and removed in the limited space between the crank shaft and the bottom pan.

In Figs. 1, 5 and 8, the engine casing appears at 1 in whose bottom is the opening 2 which is ordinarily closed by a detachable bottom pan, not shown. The fly wheel is shown at 3, and the crank shaft at 4. The bolts which secure the fly wheel 3 to the crank shaft 4 appear at 5. The crank shaft 4 is mounted in a front bearing 6, Fig. 8, a center or intermediate bearing 7, Figs. 1, 5 and 8, and a rear or innermost bearing 8, Figs. 1 and 5. The parts of the front bearing 6 are secured by bolts 9; those of the center bearing 7 are fastened by bolts 10; the innermost or third bearing 8 is secured by bolts having nuts 11.

Heretofore, so far as I am aware, no wrench has been provided which is adapted 20 to remove and replace the bolts 5 or to unfasten the bolts 9 and 10 and the nuts 11 by operations conducted through the opening 2 in the bottom of the casing 1, after the bottom pan (not shown) has been taken off. 25 The first and end bearings 6 and 8 are offset from the opening 2 and consequently a purely vertical operation cannot be carried out. The bolts 5 are located a considerable distance from the opening 2. Inside the 30 bottom of the casing 1 the space is very limited and ordinary wrenches cannot be used for the operations which have been referred to. Consequently, the practice heretofore has been to remove the entire engine and to dismantle it when it is necessary to remove the bolts 5 and replace them, and, further, to open up the bearings 6, 7, 8 so that they may be filed to take up wear and replaced and bolted in position. These 35 operations require the time of two men for a period averaging from a day and a half to two days, making the work expensive and putting the car out of commission for the period involved.

40 The foregoing operations consume the time of one man for a period of from four to five hours only when my novel wrenches are used.

The bottom pan, not shown, is first 45 detached, thus uncovering the opening 2. The next step is to remove the wire which locks the four bolts 5 in the fly wheel.

The wrench A, shown in detail in Figs. 2, 3 and 4, is now introduced through the 50 opening 2 and applied to one of the bolts 5 in the manner shown in Fig. 1. The wrench A has a hexagonal socket *a* at its left hand end which is of a size adapting it to fit the bolts 5. For the greater portion 55 of its length the wrench A is straight. It is provided with an angular part *b* of sufficient length to extend down through the opening 2 as shown in Fig. 1. The remainder of the wrench continues parallel to 60 the main stem thereof as shown at *c* and is

provided with a square socket *d* at right angles to said part *c*. The parts *c* and *d* lie below the casing 1 when the operation illustrated in Fig. 1 is being carried on.

This operation consists in rocking the 70 crank part of the wrench which is composed of the parts *b*, *c*, *d* through less than the 180° swing possible below the bottom of the casing 1, then pulling the socket *a* off of the head of the bolt 5, swinging the wrench 75 A back again and causing the socket *a* to take a fresh hold on the bolt 5; then, again swinging the wrench A to perform a further partial unscrewing of the bolt 5. This 80 operation is repeated until the bolt is removed. The other bolts 5 are then removed in the same manner. The bolts 5 then having been removed, the crank shaft 4 is completely detached from the fly wheel.

The next step is to remove the nuts 11 85 from the bolts which hold the last or third crank shaft bearing 8. The novel wrench B, shown in Figs. 5, 6 and 7, is provided for this purpose.

In Fig. 5 the wrench B is shown with its 90 hexagonal socket *e* at one end thereof engaged with the nut 11. The hexagonal socket *f* at the other end of the wrench B then lies below the bottom of the casing 1. The wrench B has a shank consisting of 95 parallel parts *g*, *h* which are laterally offset from each other as shown in Fig. 6, and are also vertically offset as shown in Fig. 7. The shank portions *g*, *h* are connected by a crank part *i* of sufficient length to dispose 100 the part *h* well below the bottom of the casing 1 when the wrench is in the position shown in Fig. 5. Similarly, when the wrench is reversed and the socket *f* engaged with the nut 11, the shank part *h* will lie 105 inside the casing 1 and the shank part *g* will lie below the casing. As shown by Figs. 6 and 7, two of the angles of the socket *e* point in the direction of the length of the shank *g*. Also, two of the sides of the 110 socket *f* lie crosswise of the shank part *h*. Furthermore, the sockets *e* and *f* are disposed at right angles to each other. The relative arrangement of the apices and the 115 sides of the sockets *e* and *f*, as above explained, enables the greatest possible effective swing of the wrench to be obtained when unscrewing, or screwing up, the nut 11, regardless of whichever socket *e*, *f*, is applied to the nut. The wrench B is made 120 double ended and reversible and constructed as described so that with the limited swing possible within the opening 2, the greatest possible speed of unscrewing or screwing may be had.

125 After unscrewing the nuts 11, one after another, by the use of the wrench B, and taking off the crank shaft bearing 8 and after re-filing the bearing 8, it is replaced and the nuts 11 screwed up to tighten the 130

bearing on the crank shaft 4. The bolts 5 are then screwed up by the reapplication of the wrench A and said bolts re-wired. This concludes the operation in so far as the fly-
5 wheel and innermost bearing 8 are concerned.

After removing the cotter pins from the bolts 10 of the center bearing 7, the wrench A is used in the manner shown by dotted lines 10 in Fig. 8, to unscrew the said bolts 10. These bolts have square heads which the socket d is adapted to fit. The wrench A is used in the reversed position from that shown in Fig. 1 and the long portion of the 15 stem is swung as far as the width of the opening 2 will permit to partially unscrew the bolt. The socket d is then removed and a fresh bite taken on the bolt. Successive operations of this character finally remove 20 the bolts 10, one after another.

The bearing 7 is then filed and replaced and the bolts 10 screwed home by the use of the wrench A to tighten up the crank shaft.

The next step is to saw off the bolts 9 and 25 remove them from the bottom and top of the casing, after which the bearing 6 can be taken out. The bearing 6 is then suitably filed and replaced.

The wrench A is then used as shown by 30 the full line position, Fig. 8, to secure the front bearing 6 together to suitably take up the crank shaft. The original bolts having been removed from that bearing and the space being limited where this bearing is 35 located, I use the two-part bolt 9' shown in Fig. 9 when replacing the bearing 6 which is screwed up by the application of the socket d thereto and the operation of the wrench A. The wrench A is swung, re- 40 moved from the bolt 9, and a fresh bite taken thereon, said operation continuing until the bearing is properly adjusted.

The bearings all having been filed, replaced, and tightened, the wear which previously existed has been taken up without 45 necessitating the removal of the engine or fly-wheel. The pan is then applied to the casing 1 to cover the opening 2.

What I claim is:

1. A wrench having a shank comprising 50 straight, parallel relatively offset portions which are connected by a short abrupt crank and sockets disposed angularly in relation to each other which are carried by the respective offset portions of the wrench. 55

2. A wrench whose shank is composed of straight, parallel sections which are connected by a crank and are relatively offset in two different directions on opposite sides of 60 said crank, and wrench sockets carried by the respective sections.

3. A wrench whose shank is composed of straight, parallel sections which are connected by a crank and relatively offset in two different directions on opposite sides of 65 said crank, and wrench sockets disposed angularly in relation to each other which are carried by the respective offset sections in angular relation to said sections.

4. A wrench whose shank is composed of 70 straight, parallel sections which are connected by a short abrupt crank and relatively offset in two different directions on opposite sides of said crank, and wrench sockets disposed angularly in relation to 75 each other which are carried by the respective offset sections, one of said wrench sockets having two of its angles in line with the section carrying said socket, the other wrench socket having two of its sides arranged crosswise of the section carrying said socket. 80

In testimony whereof I affix my signature
